[57] CLAIM

The ornamental design for a hubcap center piece for
four-wheel drive vehicles, as shown and described.

DESCRIPTION

FIG. 1 is a top plan view of a hubcap center piece for
four-wheel drive vehicle showing my new design it
being understood that the bottom is plain and unornamented; and

FIG. 2 is a side elevational view thereof, the opposite
side being a mirror image of that shown.

Fig. 1

Fig. 2
